2,204,309

DEVICE FOR HOLDING VALVE KEEPERS

Frederick Hildenbrand, Stockton, Calif.

Application March 4, 1938, Serial No. 194,011

4 Claims. (Cl. 81—5.1)

The invention relates to means to facilitate the emplacement of "keepers" on valve stems to receive therearound the spring seat collar. It is practically impossible to place these keepers in proper position manually while letting the spring seat collar down thereon, without many failures and much loss of time to say nothing of the personal injury suffered by the fingers of the worker becoming caught as the valve spring is released.

It is therefore an important aim of the invention to provide a slender pliers device which will hold the keepers in proper spaced relation to pass on each side of the valve stem, and to present them in proper operative position and so hold them on the stem while the spring valve compressed thereabove is released with its seat collar so that the latter engages properly around the keepers.

It is a further object to present a novel construction in means to hold the parts of my implement in proper operative relation and positions, and to permit the proper action of the parts to attain the placing of keepers with ease and rapidity.

Additional objects, advantages and features of invention reside in the construction, arrangement and combination of parts involved in the embodiment of the invention, as will appear from the following description and accompanying drawing representing full size, one of the possible forms of the device as heretofore actually used. In the drawing,

Figure 1 is a top view of an implement embodying the invention in inoperative position.

Figure 2 is a horizontal section through the implement.

Figure 3 is a fragmentary top view showing the extreme end portions of the jaws with the keepers engaged in the device, and as initially presented to the valve stem.

Figure 4 is a side view of Figure 3, showing the seat collar and valve spring.

Figure 5 is a view similar to Figure 3, showing the action of the device in applying the keepers to the stem in an initial stage.

Figure 6 is a similar view showing completion of the emplacement of the keepers.

There is illustrated a pair of pliers formed of sheet metal and comprising two opposed jaws 10 of identical complementary form, U-shaped in cross section and having integral handle portions 11 continued therefrom, ears 12 being formed as inward extensions from the edges of the members at the junction of the jaws and handles, on each side, so that there are four ears. These are

connected by a common pintle bolt 13 extended therethrough. The jaws are tapered suitably to avoid bulkiness at the extremities and yet ample ruggedness for rough usage in the machine shop, and when closed as in Figure 1, their inner edges are parallel, while their outer sides diverge slightly from their extremities to the pivot, and from this part the handles may diverge at a greater angle if desired. Their dimension over all on their major transverse dimension at the pivot is a little over one inch and with keepers in place the extremities are about $\frac{1}{4}$ inch wide, so that they do not occupy much space within a valve box, when in use. A spring 14 is provided to keep the handles yieldingly apart and the jaws closed, including a helix arranged loosely around the pintle 13, and arms 15 extending divergently within the bight portions of respective handles. The extremities of the jaws are shaped to present opposed curved clamping members 17 or 20 cup parts, the lower side being formed with a continuation of the lower side portion of the body of the jaw forming a step flange 16 on which a keeper may rest when engaged therein, the intermediate part being slightly offset and the upper part above the flange 16 curved so as to partly encircle a keeper. The cup parts are open at the upper side so that a keeper resting on the flange may extend upwardly from the device. The curved parts 17 may be slightly inclined inward from the flange 16 upwardly so as to conform to the customary taper of the keepers, although this is not essential.

Slidable between the jaws there is a plunger or spacer 18, formed from a blank having substantially the shape of a cross, the stem 19 of which is longitudinally slotted at 20 and has the pintle 13 engaged therethrough, while the lateral arms 21 are projected through longitudinal slots 21' in the jaws, so that the plunger is held in a plane parallel to the major plane of the device and immediately adjacent the plane of the flanges 16. Stops 22 are provided at the ends of the arms 21 to limit opening movement of the jaws and prevent the arms 21 from becoming disengaged. The body portion of the plunger is flat throughout, but at the forward end portion beyond the arms 21 side portions 23 are bent upward in parallel relation forming flanges which will receive the upper edge portions of the jaws inwardly of the cup parts slidably thereagainst, at times. The slot 20 is of a length to limit movement of the plunger outward, so that when pressed forward it stops with its extremity between the outer extremities of the jaws, as in Fig-

ure 2, and on retraction the plunger is stopped inwardly of the cup parts of the jaws, as in Figure 1. The outer end of the plunger may be slightly recessed as at 24, so that it may be easily steadied against the side of a valve stem in the use to be described.

The inner end portion of the plunger, between the handles 11 and at a suitable short distance from the ears 12 is bent upwardly at right angles and extended a distance above the handles, forming a rounded transverse finger-piece 25 by which the plunger may be manipulated as required. Pivoted on the pintle 13 over the forward part of the plunger there is a keeper or latch lever 26 which is extended rearwardly between the handles through a suitable slot 27 in the upturned finger piece 25, in which the lever is slideable. The lever is notched on one side as at 28, to receive the edge portion of the finger piece 25 therein when the lever is pressed in that direction, and the lever is extended rearwardly from this notch a distance greater than the length of the slot 20, so that it is always retained in the finger-piece. The lever 26 has an arm 29 positioned at an angle less than 180 degrees extended forwardly beyond the pintle 13 between the jaws and curved laterally toward the same side in which the notch 28 is formed; and anchored to the apertured extremity of this arm there is a contractile spring 30, engaged with a hook 31 struck from the forward part of the plunger 18, so that the latter is held yieldingly at the rear limit of its movement when the notch 28 is disengaged from the finger-piece 25, and will be drawn rearwardly from its forward position when the latch lever is moved to released position. The lateral curvature of the arm 29 causes the notched edge of the latch lever to press against the adjacent edge of the slot 27, so that when the plunger is pressed to forward position, the latch lever will automatically engage and hold it so extended.

The plunger is preferably made with a width between the jaws 10 equal to or slightly more than the diameter of a valve stem. The keepers referred to are illustrated at 32, and are used in place of the pin formerly inserted through the valve stem to support the valve spring seat or washer. The valve stem 33 is necked or reduced in diameter near its extremity as at 34, forming a recess or channel around the stem. The keepers are substantially a diametrically split conical collar set in the neck with the smaller part toward the spring 35, and are engaged in a one-piece collar 36 internally tapered to receive snugly the tapered outer faces of the keepers therein. The collar 36 is extended within the spring slightly and flanged to afford a proper seat for the spring, as is known.

In the use of the invention, for emplacement of the keepers, incident to engaging the valve spring in proper operative relation to the valve, the valve is put in place, the spring 35 and collar 36 adjusted therearound with the collar raised above the neck of the stem by a valve spring lifter 37. The neck 34 is thus exposed for emplacement of the keepers.

The jaws 10 are opened and the finger-piece 25 pressed forward until the latch 26 engages, and then the handles are compressed while the finger piece 25 is pressed first to one side and then to the other, allowing insertion of the keepers in the cup parts at respective sides of the plunger. The tool may be manipulated with one hand in this operation, while the other hand

of the user is employed to insert the keepers properly in place in the tool. Both keepers will now be held pressed by the respective jaws against opposite sides of the plunger, by which they are held spaced apart at their normally meeting sides sufficiently to admit a valve stem therebetween. The tool is now presented to the valve stem so that the notched end of the plunger abuts the side of the valve stem at the lower part of the neck 34, resting on the shoulder 38 forming the lower limit of the neck. Without compressing the handles, pressure is applied to the rear side of the finger piece 25 just sufficient to balance the tension of the spring 30, and the latch lever 26 pressed to released position. The pressure on the finger piece is then relieved sufficiently to allow the tool to be moved forwardly while the spacer draws inward as in Figure 5, which is done, the tool moving the keepers beside the neck portion of the stem 35. The spring 14 causes the jaws to continue inward pressure, serving to press the keepers inward against the plunger and the neck upon which they slide until they meet at the far side. Forward movement of the tool is then discontinued, while the plunger is allowed to be drawn from between the keepers, when they will be snapped together by the jaws of the tool under action of the spring 14. My tool is left so engaged with the keepers while the spring lifter 31 is operated to lower the collar around the upper parts of the keepers and the collar is allowed to press the jaws of the tool downward or the tool is pressed downwardly manually until it clears the keepers, at which time the collar will be so closely engaged with them as to retain them until they come to a seat within the collar.

In regulating the movement of the spacer from extended position, the device may be grasped by one handle, as at A, Figure 1, with the end of the thumb firmly pressed against the finger-piece 25, as a brake, and the backward movement of the spacer thus controlled properly by a gradual bending of the thumb or slipping the handle while in grasp. This avoids accidental pivotal movement of the handles which may occur if they are retained both within the grasp. Also, the forward part of the device may be grasped between the thumb and forefinger as at B, Fig. 2, just back of the arms 21, and the slip of the spacer regulated by the pressure of the fingers against the jaws, as a brake, allowing the jaws to gradually slip forward.

I claim:

1. A device of the character described comprising relatively movable clamping members having shank portions longitudinally slotted and pivoted mountings therefor, a spacer longitudinally slideable between the clamping members and slidably mounted with respect to said mountings, and having arms extended through the slots of respective shanks and beyond, said spacer having an operative piston when moved to a position between the clamping members whereby to hold the clamping members apart, said clamping members and spacer being constructed to permit closing of the clamping members when the spacer is at the retracted or inoperative position.

2. A device of the character described comprising relatively movable clamping members and means to operate them, a spacer longitudinally slideable between the clamping members and including a right angular portion having a slot, a lever device pivoted on the spacer and

extended through the slot, said lever device being mounted to swing toward and away from an edge of the slot, the lever being notched to receive said edge as a detent at one position of the spacer, 5 said lever further having an arm at an angle of less than 180 degrees to said lever in the direction of said edge and notch, and a spring connected between the extremity of said arm and the spacer, for the purposes described.

10 3. A device of the character described comprising pivoted jaws having opposed cup portions at their extremities and having operating handles oppositely extended from the pivot, spring means to close the jaws, a spacer slideable longitudinally between the jaws having an inner part longitudinally slotted, said pivot including a pintle through the slot, a lever pivoted on the pintle beside the spacer, the inner part of the spacer having a finger-piece extended laterally of the plane of oscillation of the pivoted members, said lever having a notch to engage one edge of the finger-piece as a detent, 15 said lever further having an arm extended obliquely of the path of sliding movement of the spacer and a spring connected between the ex-

tremity of said arm and the spacer, tending to draw the spacer to one limit of its movement, and said arm being inclined in a direction to cause said notch to be pressed toward said edge of the fingerpiece.

5 4. A device of the character described comprising jaws having opposed cup portions at their extremities and having oppositely extended operating handles connected thereto, spring means to close the jaws, a spacer slideable longitudinally between the jaws and having a laterally presented edge portion, means to hold the spacer in slideable relation between the jaws, a lever pivoted inwardly of the jaws forwardly of said edge portion, said lever having a notch extending from one side thereof to engage said edge portion at times and having a forwardly extended arm obliquely extended with respect to the lever in the same direction as the notch, and a spring connected between the extremity of the arm and the slide whereby to draw the slide rearwardly and press the notched side of the lever against said edge portion.

FREDERICK HILDENBRAND. 25
